UNITED STATES PATENT OFFICE.

CARL SAHLER, OF COLOGNE, PRUSSIA, GERMANY, ASSIGNOR TO E. A. HERBERTZ, OF SAME PLACE.

GRATE.

SPECIFICATION forming part of Letters Patent No. 390,191, dated September 25, 1888.

Application filed February 29, 1888. Serial No. 265,704. (No model.)

To all whom it may concern:

Be it known that I, CARL SAHLER, a subject of the King of Prussia, German Emperor, residing at the city of Cologne-on-the-Rhine, in the Kingdom of Prussia, German Empire, have invented certain new and useful Improvements in Grates, of which the following is a specification.

This invention relates to improvements in fire-places for boilers, stoves, and furnaces.

The object of my invention is to dispense with the ordinary metal grate-bars and to provide a grate which is durable, not apt to be destroyed by heat or clogged by slag and clinkers, and in which the draft can be regulated very readily.

The invention consists in the construction and combination of parts and details, as will be fully described and set forth hereinafter, and then pointed out in the claims.

In the accompanying drawings, Figure 1 is a vertical transverse section of a horizontal boiler provided with my improved grate. Fig. 2 is a vertical longitudinal section of the same. Fig. 3 is a vertical transverse section of a vertical boiler provided with my improved grate. Fig. 4 is a vertical transverse section of a stove provided with my improved grate.

Similar letters of reference indicate corresponding parts.

In place of the usual metal grate-bars I use plates covered with fire brick. As shown in Fig. 1, I provide two parallel plates, A, having upwardly-projecting flanges along the side edges, and on said plates I apply the fire-brick B, which has its top beveled from the longitudinal central line toward the side edges. Between and slightly above the plates A, I provide a bar, C, parallel with said plates and provided on its top with a covering, D, of fire-brick, which is also beveled from the longitudinal central line toward the side edges. The brick-work E, in which the boiler F is mounted, is cut away at part of the length of the sides and at the front of the boiler, and said front part of the brick-work is supported by columns G. Angle-irons H are secured to the edges of the brick-work, and between them and the fire-brick B air-passages a are formed.

Air-passages b are formed between the opposite sides of the fire-brick Band the fire-brick D.

At the bridge-wall J the angle-iron K is provided, between which and the fire-brick B an air-passage is formed, and at the bottom part of the front of the brick-work the angle-iron L is provided. Air-passages are thus formed entirely around the plates and bars supporting the fire, and through said air-passages the air can pass to the fire.

To permit of regulating the quantity of air passing to the fire, the plates A are made vertically adjustable in some suitable manner.

In Figs 1 and 2 the plates A are hinged at their inner ends to the bridge-wall J, and their front ends are supported by chains M, passed over pulleys N and carrying a suitable counter-weight, or said chains can be connected with a winding device to raise the front ends of the plates A.

In Fig. 3 the circular plate A' carries the fire-bricks B', and an annular air-passage is formed between the bottom of the boiler S and the rim-part of the fire-brick B'. The plate A' is provided with arms O, that can engage notches in standards P, supporting the boiler S, thus permitting of raising or lowering the plate A'.

In the construction shown in Fig. 4 the plate A² is hinged to the bottom of the stove Q and carries the fire-brick B². In this case the fire-brick is provided with a V-shaped annular groove near its rim—that is, the top of the fire-brick is inclined downward from the center toward a circular line a short distance from the rim and from said line upward toward the rim.

My improved fire-brick grates do not burn out as rapidly as the ordinary grate-bars, do not warp, do not become clogged by cinders or slags, and retain the pulverized or granulated fuel that usually drops between the bars of ordinary grates.

Having thus described my invention, I claim as new and desire to secure by Letters Patent—

1. The combination, with a boiler, furnace, or stove, of a plate below the same and a covering of fire-brick on said plate, the surface of said fire-brick being a short distance from the

walls or support of the stove or boiler, whereby air-passages are formed between said fire-brick covering and the walls or support of the stove or boiler, substantially as herein shown and described.

2. The combination, with a boiler, stove, or fire-place, of a bar extending longitudinally under the boiler, a fire-brick covering upon said bar, and two vertically-adjustable plates below the spaces between the fire-brick covering on the bar and the walls of the boiler-support, and fire-brick covering on said plates, substantially as herein shown and described.

3. The combination, with a fire-box, of a

plate slightly larger than said fire-box and below the bottom edge of the same, and which plate is capable of adjustment toward or from the bottom of the fire-box, and a covering of fire-brick upon said plate, substantially as herein shown and described.

In testimony whereof I have signed my name to this specification in the presence of two subscribing witnesses.

CARL SAHLER.
